UNITED STATES PATENT OFFICE

ALFRED T. YUNGMAN, OF AKRON, OHIO, ASSIGNOR TO THE VAUGHN MACHINERY COMPANY, OF CUYAHOGA FALLS, OHIO, A CORPORATION OF OHIO

WIRE DRAWING MECHANISM

Application filed February 7, 1929. Serial No. 338,142.

The present invention relates, as indicated, to a wire drawing mechanism, and more particularly to that type of wire drawing bench which comprises a plurality of blocks carrying dies and drawing drums. The primary object of the invention is to increase the flexibility of use of such a bench. To the accomplishment of the foregoing and related ends, said invention, then, consists of the means 10 hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a side elevation of a drawing bench 20 of the type described; and Fig. 2 is a plan view thereof.

According to my invention, the drawing bench comprises one or more bottom cases or housings 2 and 3, each of which is provided 25 with a cover section as at 4 and 4', the joints between the housings and covers being on the center lines of the bearings for transverse shafts later to be described. The casing 2 mounts a drum 5 and a gear 6 upon a trans- 30 verse shaft 7, said gear 6 meshing with a pinion 8 carried upon a parallel shaft 9 mounted in said above-mentioned bearing. Another drum 10 and a gear 11 of smaller pitch than said gear 6 are mounted in said 35 housing 2 upon a shaft 12 parallel with, and in the same horizontal plane with, said shaft 7, said gear 11 also meshing with said pinion 8. The drums 5 and 10 are of equal diameters, and consequently it will be seen that 40 the drum 10 will draw a greater length of wire in a given period than will the drum 5.

In the bearing provided between the housing 3 and its cover 4', there is mounted a shaft 14 similar to the shaft 9, and said shaft 45 carries a pinion 13 meshing with gears 15 and 16 carried upon shafts 17 and 18 which also carry drums 19 and 20, all of the above being similar to the arrangement in the housing 2.

50 A motor 21 is mounted adjacent said hous-

ings, and the spindle 22 thereof is connected through a flexible unit 23 to a shaft 24 carrying a worm 25 within a casing 26, said worm meshing with a worm wheel (not shown) on the shaft 9. The shaft 24 continues beyond the casing 26 and is secured through a flexible coupling 27 to the shaft 28 of a second worm 29 within a casing 30, said worm 29 meshing with a worm wheel (not shown) carried by the shaft 14. The worms 25 and 26 are so dimensioned that the drum 19 rotates slightly faster than the drum 10.

Rollers 31 and 32 guide a piece of wire which is threaded through dies 33, 34, 35, 36, and 37. Suitable mechanism indicated generally at 38 is provided for rotating said dies. It will be understood that the wire is threaded through the die 33, wrapped two or three times about the drum 5, threaded through the die 34, wrapped about the drum 10, threaded through the die 35, wrapped about the drum 19, threaded through the die 36, wrapped about the drum 20, threaded through the die 37, and drawn away from the machine by suitable mechanism and wound. Each die reduces the cross-sectional area of the wire, and it may be supposed, for the purposes of this discussion, that the die 33 brings the diameter of the wire to one-eighth 80 of an inch, the die 34 brings it to seven-sixty-fourths of an inch, the die 35 brings it to three-thirty-seconds of an inch, the die 36 brings it to five-sixty-fourths of an inch, and the die 37 brings it to one-sixteenth of an 85 inch. A trough for drawing lubricant is illustrated at 45.

According to usual practise, the winding mechanism above mentioned which also usually acts as the means for drawing the wire through the last die 37, is inflexibly inter-gearred with the drums 5, 10, 19, and 20. Where such is the case, however, it will be impossible to draw efficiently on the machine illustrated, a wire having a cross-sectional 95 diameter of, say, three-thirty-seconds of an inch, since the winding mechanism, geared to rotate at a proper speed to draw the wire through the die 37, would operate too fast to draw the wire through the die 35 as the 100

last die; i. e., with the winding mechanism or finishing drum geared in this manner, any size wire drawn must be finished on die 37 and always at the same speed. To increase the 5 flexibility of the machine, then, I provide at the right end of the machine, a separate drawing block unit 39 comprising a drum or reel 40 mounted upon a vertical shaft 41, said shaft 41 carrying a worm wheel 42 cooperating with a worm 43 upon the spindle of an adjustable speed motor 44. Obviously, with this construction, as the finished size of wire increases, the power required will increase in proportion to the increased area of the 10 wire. With my improved design, when drawing the larger sizes as in above example, the speed of the finishing block can be reduced to correspond with that of any of the drums and the power required thereby limited to a figure no greater than the amount necessary to draw the smaller wire at the speed of the last drum. A machine of ordinary fixed-speed-windup construction designed to produce a certain size wire at the 15 speed of the last drum will not have power enough to draw any larger sizes. The same machine with my improved adjustable speed windup will be able to draw any size down to that of the original rod without overloading. 20 The savings in machine cost due to this feature are obvious.

It will be clearly seen that, through this provision, I have made it possible to use the 25 herein-disclosed machine to draw wire to any diameter from, say, one-eighth of an inch to one-sixteenth of an inch, using gears and motive power no larger than required to draw one-sixteenth inch from one-eighth inch in four drafts on a machine with intermediate drums and finishing drum intergeared. 30 Thus if it is desired to draw wire to a sectional diameter of one-eighth of an inch, said wire is threaded through the die 33 and carried directly to the drum 40. The motor 44 is then energized to rotate the drum 40 at the proper speed to draw wire through the die 33 alone. If, on the other hand, it is desired to draw wire to three-thirty-seconds of 35 an inch diameter, the wire is threaded through the die 33, wrapped about the drum 5, threaded through the die 34, wrapped about the drum 10, threaded through the die 35 and then carried to the drum 40.

The motors 21 and 44 being energized, and 40 the motor 44 being driven somewhat faster than in the previous case, the wire may be drawn through the dies 33, 34, and 35 to obtain the desired reduction. From the above description it will be apparent that, by varying the speed at which the motor 44 rotates the drum 40, it will be possible to draw wire through any selected number of dies mounted upon the described machine, and that said machine, with the provision of the separate 45 drawing unit 39 is infinitely more flexible

than a machine of which the last drum is inflexibly intergeared with the other drawing drums of the machine.

While I have disclosed a machine including a finishing drum driven by a separate motor, it is to be understood that I might alternatively use a finishing drum driven from the main drive motor 21 through the medium of change-speed gears or of a variable speed drive such as, for instance, a Reeves unit.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. The combination with a drawing bench comprising a pair of transverse shafts, a drum on each of said shafts, a gear on each of said shafts, said gears having different pitch diameters, a shaft arranged intermediate said transverse shafts and carrying a gear in mesh with said transverse shaft gears, a worm wheel on said intermediate shaft, a worm mounted for cooperation with said worm wheel and means for driving said worm, of a separate, self-contained winding unit mounted at one end of said bench and comprising a drum and an adjustable speed motor for driving the same.

2. In an apparatus of the character described, a means for selectively driving a series of drawing drums comprising a pair of transverse shafts, a drum on each of said shafts, a gear on each of said shafts, said gears having different pitch diameters, a shaft arranged intermediate said transverse shafts and carrying a gear in mesh with said transverse shaft gears, a worm wheel on said intermediate shaft, a worm mounted for cooperation with said worm wheel, and means for driving said worm.

3. In combination, a multiple-drum drawing bench including a plurality of dies, a drawing drum for each die, means associated with said drums adapted to drive them at speeds having fixed predetermined differentials, a finishing die, and a winding unit having a winding drum thereon adapted to draw a wire through said finishing die at a speed adjustable to correspond to the number of dies in use, the drive for said winding drum being separate and independent from that of said drawing drums, in order that said winding drum may be driven in combination with any number less than the total number of drawing drums to provide a multiple purpose drawing machine.

Signed by me this 31st day of January, 1929.

ALFRED T. YUNGMAN.
